LIGHT ACTUATED CIRCUITS

Bernard G. Radin, Detroit, Mich., assignor to Ford Motor Company, Dearborn, Mich., a corporation of Delaware

Application June 28, 1956, Serial No. 594,448

5 Claims. (Cl. 250—214)

This invention relates to light actuated circuits and more particularly to a circuit which is adapted to be used with a motor vehicle headlight arrangement which automatically changes the intensity of the headlights upon receiving a signal of light from oncoming vehicles.

With this invention it is possible to have a motor vehicle automatic headlight dimming assembly by using a series of resistances and one vacuum tube with one photoconductive cell. A principle of this invention is to connect a control grid of the vacuum tube to a photoconductive cell which cell changes its resistance upon receiving a light signal thereby changing the voltage level of the grid causing said tube to conduct. When the tube is conducting, a relay energizes a switch which changes a second resistance in the grid circuit, giving the tube a different sensitivity to light so that a first increment of light differential will cause the tube to fire but a second and different light differential will cut off the tube. This is done so that when the headlights are on high beam a small increment of increased received light will switch them to low but a large increment of decreased received light will be necessary to switch them back to high so that it will be less likely that an oncoming driver will have a high beam switched on into his eyes due to some small reduction in light that may be caused by a turn or dip in the road or one car turning off in front of another. Heretofore, a much more complicated system has been necessary to provide the functions outlined above.

Other objects and advantages of this invention in addition to further explanation of the above objects will appear in the following detailed descriptions of two embodiments of this invention which will be best understood when considered in connection with the following drawings in which:

Figure 1 is a schematic drawing showing a circuit for one embodiment of this invention and Figure 2 shows a second embodiment of this invention.

Looking at Figure 1 is seen vacuum tube 21 which may be a standard tube with the designation 12K5 as may be obtained from Tungsol having anode 22, control grid 23, accelerator grid 24, and cathode 25. Photoconductive cell 27 is connected between grid 23 and switch 28 and is of the type which has its resistance lowered upon the reception of light. When switch 28 is in its upper position to which it is spring urged, connection is made to resistance 31 and then to plus voltage line 32. When switch 28 is in its lower position, as it would be when relay 29 is energized due to the conducting of tube 21, connection is made to resistance 34 and then to plus voltage line 32 which puts grid 23 at a higher voltage since the drop between resistance 34 and line 32 will of necessity be less than that between resistance 31 and line 32 due to the presence of resistance 33 which is of approximately equal value to resistances 31 and 34. Terminal 37 leads to control beam circuit relay, not shown, which relay is energized to a low beam position when relay 29 is energized closing switch 38. Current

2

cut off in tube 21 and hence relay 29 will open switch 38, de-energizing the control beam relay, causing the high beam to be actuated.

In the operation of the embodiment shown in Figure 1 5 light cell 27 is positioned to receive the light from oncoming vehicles, and when it so does, its resistance is lowered, raising the potential of grid 23 causing tube 21 to conduct. Relay 29 is energized causing switches 38 and 28 to change position. Switch 28 will move downwardly 10 into the low beam position while switch 38 will make contact with terminal 37 actuating the low beam circuit. With switch 28 in the lower position the voltage of grid 23 is raised a pre-determined amount so that the resistance in tube 27 must drop a proportionately larger 15 amount to cause tube cutoff and resume the high beam position. This tends to prevent the high beams from being applied when a slight decrease in light upon tube 27 occurs such as might happen when the oncoming vehicle either travels over a dip in the road or turns slightly or 20 the oncoming car turns off the road but is followed by a second oncoming car.

The components of the circuit shown in Figure 1 may be as follows. Photo cell 27 may be an RCA tube-type C7218. Tube 21 may be a Tungsol 12K5 tube. Battery 25 41 may supply 14.4 volts direct current while resistances 42 and 43 may be 100 and 27 ohms respectively. Resistances 31, 33, 34 may all be 5 kilohms while resistance 44 30 may be 2 megohms. Resistances 31 and 34 may be varied to obtain the desired times for tube firing and cutoff. In Figure 2 is shown a second circuit for accomplishing the above mentioned objectives with the additional advantage of eliminating a switch. Battery 51 supplies approximately 14.4 D.C. volts to the circuit. Resistances 52, 53 may be respectively 100 and 27 ohms and 35 control the voltages of accelerator 54 and cathode 55 in tube 50 which is in this embodiment also a standard 12K5. Resistance 58 and photo cell 59 control in part the voltage of grid 56, and resistance 58 may be 10 kilohms while tube 59 is an RCA tube C-7218. Resistance 61 is 330 kilohms while resistance 62 is variable with a maximum value of 3 megohms. Relay 63 when energized switches blade 64 from an upper or high beam position to the lower or low beam position. Terminal 65 40 leads to the control beam circuit and when connected to switch 64 actuates the low beam and when disconnected the high beam is actuated.

In the position shown switch 64 is in the high or upper position and tube 50 is not conducting. With switch 64 in the upper position resistance 62 is by-passed thereby 50 putting the potential of grid 56 at a lower level than if resistance 62 is in the circuit. When tube 59 receives light from an oncoming vehicle its resistance is lowered raising the voltage of grid 56 causing tube 50 to fire. After tube 50 conducts, relay 63 is energized actuating switch 64 to 55 a lower position. This activates a low beam circuit and also puts resistance 62 into the grid circuit further raising the grid voltage so that a large increment of decreased light received by cell 59, causing a corresponding resistance increase, is necessary before tube 50 is cut off by grid 56.

This invention may be used in addition to a manual switch for changing from high to low beams. An example of this kind of circuit is my copending application filed June 29, 1953 with Serial Number 364,621, now 65 United States Patent 2,763,809. Until the vacuum tube warms to operating condition a time delay switch may be used to hold the headlights in low beam if desired. Also, the light sensitive photoconductive tube may be placed between the control grid and negative voltage so 70 that light from an oncoming vehicle will cut off the firing of the vacuum tube.

It will be understood that the invention is not to be

limited to the exact construction shown and described, but that various changes and modifications may be made without departing from the spirit and scope of the invention, as defined in the appended claims.

What is claimed is:

1. In an automatic headlight dimmer for direct operation on a vehicle low potential electrical power source the combination comprising a vacuum tube with a control grid interposed between an anode and a cathode, the anode of said vacuum tube being connected to receive a positive potential from the positive terminal of said electrical power source and the cathode of said vacuum tube being connected to said power source to receive a lower potential than said anode, a light sensitive variable resistance having a first and a second terminal and being connected at said first terminal to said grid, a first resistance and a second resistance, said first resistance having a smaller value than said second resistance, each of said resistances having one terminal connected to the positive terminal of the electrical power source and the other terminal connected to the negative terminal of the electrical power source, a switching means having a first, a second and a third terminal, said first terminal being capable of being selectively connected to either said second terminal or said third terminal, the first terminal of said switching means being connected to the second terminal of said light sensitive variable resistance, the second terminal of said switching means being connected intermediate the ends of said first resistance, the third terminal of said switching means being connected intermediate the ends of said second resistance for supplying a higher voltage to the third terminal of said switching means than the voltage supplied to said second terminal from said first resistance, said first terminal of said switch being connected to said second terminal of said switch when said vacuum tube is non-conducting thereby placing a predetermined potential on said control grid, means positioned between the anode of said vacuum tube and the positive terminal of the electrical power source for connecting the first terminal of the switch to the third terminal of said switch upon conduction of said vacuum tube in response to a given light intensity impinging upon said light sensitive variable resistance whereby the grid potential on said control grid is increased above the predetermined grid potential present when said vacuum tube is in a non-conducting state.

2. In an automatic dimmer for direct operation on a vehicle low potential electrical power source the combination comprising a vacuum tube, said vacuum tube including a cathode, an anode and a control grid, the anode of said vacuum tube being connected to receive a positive potential from the positive terminal of said electrical power source and the cathode of said vacuum tube being connected to receive a lower potential than said anode, a light sensitive variable resistance having one terminal connected to said grid and the other terminal connected to receive a positive potential from the positive terminal of said electrical power source, means positioned between said grid and said cathode for biasing said grid to a predetermined potential, a resistor connected in series with said light sensitive variable resistor and between the grid of said vacuum tube and the negative terminal of said electrical power source, a relay connected between the anode of said vacuum tube and the positive terminal of the electrical power source adapted to be energized when said vacuum tube conducts, said relay including a switch having a first, a second and a third terminal, said relay adapted to connect said first terminal of said switch with either said second terminal or said third terminal, the first terminal of said switch

being connected to the negative terminal of the electrical power source and to one terminal of said resistor, the second terminal of said switch being connected to the other terminal of said resistor with the third terminal

5 being adapted to actuate an external circuit, the first terminal of said switch being connected to the second terminal of said switch when said vacuum tube is non-conducting thereby shorting out said resistor, said vacuum tube being rendered conducting by the impingement of 10 light on said light sensitive variable resistance thereby energizing said relay and disconnecting the first terminal of said switch from the second terminal of said switch and effectively placing said resistor in series with said light sensitive variable resistance thereby raising the 15 potential on said grid by the amount of the potential drop across said resistor.

3. In an automatic dimmer, an electron device having an output circuit and a control circuit, a first voltage source and a second voltage source for supplying voltages of different values, a light sensitive variable resistance connected in the control circuit of said electron device, and means positioned in the output circuit of said electron device for connecting the output of the first voltage source to the control circuit when light of a selected intensity 20 impinges upon said light sensitive variable resistance and for connecting the output of the second voltage source to the control circuit when light of an intensity above said selected intensity impinges upon said light sensitive variable resistance.

4. In an automatic headlight dimmer for operation on a power source, an electron device having an output circuit and a control circuit, a first voltage divider and a second voltage divider connected in parallel across said power source for producing voltages of different values, 25 a light sensitive variable resistance connected in the control circuit of said electron device, and means positioned in the output circuit of said electron device for connecting the output of the voltage divider producing the lower voltage to the control circuit when light of a selected intensity impinges upon said light sensitive variable resistance and for connecting the output of the voltage divider producing the higher voltage to the control circuit when light of an intensity above said selected intensity impinges upon said light sensitive variable resistance.

5. In an automatic headlight dimmer for operation on a power source, the combination comprising a vacuum tube having an anode, a cathode and a control grid, the anode of said vacuum tube being connected to receive a positive potential from said power source, said cathode being connected to receive a lower potential from said source than said anode, a first voltage divider and a second voltage divider connected in parallel across said power source for producing voltages of different values, 30 a light sensitive variable resistance connected to the grid of said vacuum tube, and means positioned in the output circuit of said vacuum tube for connecting the output of the voltage divider producing the lower voltage to said light sensitive variable resistance when said tube is in a non-conducting state and for connecting the output of the voltage divider producing the higher voltage to said light sensitive variable resistance when said vacuum tube is in a conducting state.
